WRENCH

Alexander Boynton, San Antonio, Tex.

Application April 8, 1939, Serial No. 266,758

4 Claims. (Cl. 81—179)

My invention relates to wrenches or tongs and particularly, to pipe wrenches.

The objects are to provide a wrench that (1) will not mash the pipe, (2) will not score or cut the pipe by deeply embedding teeth, as many other wrenches do, (3) will not slip on the pipe, (4) may be quickly applied.

I accomplish the foregoing objects by means of a plurality of pipe gripper dogs urged inwardly by a roller engaging between two surfaces, one of which is eccentric to the pipe; these rollers being normally urged by a spring adapted to hold pipe grippers apart so as to admit the pipe, as will more fully appear from the accompanying drawings in which:

Fig. 1 is a top plan view of the preferred form of the wrench.

Fig. 2 is a section on the line 2—2, Fig. 3. Figure 3 is a side view of the wrench shown in Figs. 1 and 2.

Fig. 4 is a section on the line 4—4, Fig. 1.

Fig. 5 is a side view of one of the rollers.

Fig. 6 is an end view of one of the pipe grippers in Fig. 2.

Fig. 7 is an inside view of the part shown in Fig. 6.

Fig. 8 is a top view of a modified form of the wrench shown in Figs. 1, 2, and 3.

Fig. 9 is a section on the line 9—9, Fig. 10.

Fig. 10 is a side view of the wrench shown in Figs. 8 and 9.

Fig. 11 is a section on the line 11—11, Fig. 3.

Fig. 12 is an end view of the pipe gripper in Fig. 9.

Fig. 13 is an inside view of the part shown in Fig. 12.

Similar characters refer to similar parts throughout the several views of each embodiment.

With particular reference to Figs. 1, 2, and 3, the handle member 1 is hinged to double hinged shell or head 5 by a hinge bolt 4; the single hinged shell or jaw 7 being also hinged upon head 5 by a hinge bolt 6. The arm 1a of handle member 1 has its extremity forked to receive the roller wheel 2 mounted within the forks upon axle bolt 3. The groove 7a, exterior of shell 7, is adapted to receive the roller wheel 2 for sufficient depth to act as a guide for the roller in the path of its travel. The length of groove 7a is such as will allow the roller 2 to remain within it while the dogs of the wrench are engaged between their most expanded and their most contracted positions upon pipe 18 so that the roller 2 transmits a thrust from the handle 1 to the

jaw to retain the tong about the pipe and in gripping position.

The angle between arm 1a and a line tangent to groove 7a at the point where the roller wheel 2 first contacts this groove when the handle member 1 is moved clockwise, is such that the roller wheel will urge pipe gripper dogs together, as appears in Figs. 1 and 2. The stop bumper extension 1b is adapted to engage upon the surface 5c on the head 5 when the handle member 1 has been rocked anti-clockwise with relation to the shells 5 and 7 far enough to allow shell 7 to clear the roller wheel 2 as the wrench is opened. The shell 7, hinging upon bolt 6, may then be opened far enough to admit the pipe 18; the further opening swing of shell 7 being arrested by a stop bumper 5b on the head contacting the surface 7b on the jaw.

The rollers 12 may have teeth 12a enmeshing with and between the teeth 5a of head 5 and teeth 15b of the pipe grippers or dogs 15. The teeth 15b are concentric with pipe 18, but the teeth 5a are tangent to a circle somewhat larger than the pipe, so that the pipe grippers 15 will be forced inward upon pipe 18 when the rollers 12 are caused to turn clockwise by the handle member 1 being moved so that the roller wheel 2 will engage within the groove 7a of the shell 7. The number of teeth 5a and 15b and the direction of the tangent are such that the rollers 12, in their travel, will permit the pipe grippers 15 to expand far enough to loosely surround the pipe 18 and contract enough to engage the teeth 15a so tightly upon the pipe that the wrench and pipe will then turn together.

Each of the rollers 12 are formed with a short spindle 12b on one end and a long spindle 12c on the other end. Each of these spindles are received for a short distance within shallow bores in the plates 8, 9, 10, and 11, as appears in Fig. 4. These plates are held in place by screws 14 as illustrated in Fig. 1, and each of these plates has a flange 11a engaging within grooves 15c in the pipe grippers 15 as seen in Figs. 2, 6, and 7. This engagement of the flanges 11a within grooves 15c secures the assembly of pipe grippers 15.

Flat springs 16, secured upon flanges 11a by rivets 17 (see Fig. 2), fit into the grooves 15c and are adapted to resiliently urge the pipe grippers 15 upon the rollers 12 which are thereby kept enmeshed with their mating teeth on both sides, as appears in Fig. 2.

Each of the spring wires 13 has one end received within an opening thru the long spindle

12c where it may be secured by electric spot weld 13a, see Fig. 5. These spring wires, exerting an unwinding torque, are installed wrapped partially around the spindles 12c and are received within the grooves 5d in the shells 5 and 7, as appears in Fig. 2, in which figure the rollers 12 are in the middle of their travel with the pipe grippers 15 loosely engaged upon pipe 18. When the wrench is freed from the pipe the unwinding action of these springs, which are never completely withdrawn from the grooves 5d, will force the rollers 12 to turn clockwise and, thus, automatically engage near or between the end teeth, indicated at 5aa and 15bb, Fig. 2; this being the most open position of the pipe grippers 15.

To apply the wrench, shell 7 is swung open to admit the pipe 18. The handle member 1 is then moved toward the operator, who is assumed to be positioned on the roller wheel side of the wrench. A snappy pull of the handle will then cause the roller wheel 2 to travel clockwise in slot 7a; thereby urging the shells 5 and 7 toward each other and the pipe grippers 15 upon the pipe by the rolling action of rollers 12 which then turn clockwise and travel away from the end teeth 5aa and 15bb while the pipe grippers are closing upon the pipe. The wrench may be freed from the pipe by thrusting the handle away from the operator until stop bumper 1b engages the surface 5c, at which time the roller wheel 2 will clear shell 7 and permit this shell to be opened until stop bumper 5b engages upon the surface 1b; thus conveniently arresting the opening movement when the opening is ample to admit the pipe.

Figs. 8, 9, and 10 illustrate a modified form of this invention. The parts of the modified form and of the preferred form, indicated by the same reference characters, are the same in construction and purpose. In the modification all parts are primed where these parts are essentially different from the somewhat similar parts in the preferred form. While several parts in the modification closely resemble similar parts in the preferred form, there are essential differences; the principal difference being, that the teeth on pipe grippers are eccentric with reference to the pipe and the teeth in the shell are concentric therewith in this form; while in the preferred form the teeth on pipe grippers are concentric with reference to the pipe and the teeth in the shell are tangent to a circle somewhat larger than the diameter of the pipe upon which the wrench is adapted to be used.

By referring to the preferred form, illustrated in Figs. 1 to 7, both inclusive, and the specification thereof, the construction of this modification will be clearly understood; attention being directed to the fact that the only parts in the modification which essentially differ from the similar parts in the preferred form are the double hinged shell or jaw 5', teeth 5a', single hinged shell or jaw 7', pipe grippers 15', and pipe gripper roller teeth 15b'.

It will be noted in Fig. 9 that the pipe grippers 15', having teeth 15a' to engage the pipe, are eccentric with reference to the pipe, in order to provide a thickening of the grippers toward one end in order that the teeth 15b', coacting with the concentric teeth 5a' of the hinged shells 5' and 7', will urge the pipe grippers upon the pipe when the wrench handle is moved clockwise and away from the pipe when the handle is moved anti-clockwise. It will be understood, of

course, that the terms "clockwise" and "anti-clockwise," as relates to the movements of the wrench handle and pipe gripper dogs, become reversed in both forms of the invention as the wrench is reversed in operation from the positions shown in the figures discussed by way of illustration.

It is apparent that many minor changes and substitutions can be made within the scope of the stated objects and appended claims, and I reserve the right to make such changes and substitutions.

What is claimed is:

1. In a pipe wrench the combination of a pair of jaws adapted to surround a pipe, pipe gripping dogs within said jaws, a loose eccentric tongue and groove connection between said jaws and dogs whereby the dogs are movable radially and circumferentially, opposed converging surfaces on said dogs and jaws, and roller means between and having a driving connection with said surfaces for moving the dogs inwardly when the jaws are rotated relative to the dogs.

2. In a pipe wrench the combination of a pair of jaws adapted to surround a pipe, pipe gripping dogs within said jaws and movable relative thereto, opposed converging surfaces on said jaws and dogs, and rollers drivably engaging said surfaces and adapted to urge the dogs inwardly when a rotative effort is applied to the jaws to urge the rollers in the direction of convergence, and resilient means normally tending to rotate said rollers and move the dogs to retracted position.

3. In a pipe wrench, the combination of a pair of jaws adapted to surround a pipe, means for holding the jaws in predetermined relative position about the pipe, pipe gripper dogs within said jaws, said grippers having internal teeth conforming with and adapted to embed within said pipe to impart rotary force thereto, a group of concentric teeth on the exterior of each of said grippers, spaced groups of teeth opposed to said first groups interior of said jaws and on lines tangent to a circle somewhat larger than said pipe, a roller having teeth engageable between each pair of said opposed groups, a loose annular tongue and groove connection between said jaws and gripper dogs and means therein for radially forcing said grippers to engage said rollers between said opposed groups of teeth, means on said rollers to normally position same so as to resiliently hold said grippers radially expanded.

4. In a pipe wrench, a jaw assembly including a pair of jaws adapted to surround a pipe, means for holding said jaws in predetermined relative position about the pipe, pipe gripper dogs within said jaws, said grippers having internal teeth conforming with and adapted to embed within said pipe to impart rotary force thereto, a group of teeth on the exterior of each of said grippers arranged eccentrically relative to the internal teeth, spaced groups of concentric teeth opposed to said first groups interior of said jaws, a roller having teeth engageable between each pair of said opposed groups, a loose annular tongue and groove connection between said jaws and grippers and means therein for radially forcing said grippers to engage said rollers between said opposed groups of teeth, means on said rollers to normally position same so as to resiliently hold said grippers radially expanded.

ALEXANDER BOYNTON.
